UNITED STATES PATENT OFFICE.

HARRY D. MADDEN, OF NEWARK, NEW JERSEY, ASSIGNOR TO WESTINGHOUSE LAMP COMPANY, A CORPORATION OF PENNSYLVANIA.

MACHINE FOR DEFORMING GLASS ARTICLES.

Application filed December 10, 1920. Serial No. 429,623.

My invention relates to machines for reducing the perimeter of a portion of the length of a glass tube, rod or analogous body, and the object of the invention is the provision of a machine for the above purpose which shall be simple in construction and automatic in operation and which shall expeditiously carry out the necessary functions to form the desired shape in large 10 quantities of tubes.

It has heretofore been the practice to exhaust incandescent-lamp bulbs by forming a tubulation on the large end of the bulb and providing a constricted portion adjacent 15 the point at which the tubulation is effected. The constriction in a tube, according to this method, is formed by fusing the end of the tube to the bulb and afterwards drawing the tube away from the bulb.

20 In the manufacture of a so-called tipless lamp, or lamp in which the bulb is exhausted through the base end of the bulb, it is desirable to use a tube having a constriction a substantial distance from its ends. 25 In practice, such exhaust tubes are consolidated in the exposed end of a lamp mount and provide a suitable aperture for exhaust purposes. My invention contemplates an automatic machine for providing a constriction in tubes intended for use in the manufacture of the tipless lamps.

In the accompanying drawing, Fig. 1 is a side elevation of the machine, partly in section, some of the tube-gripping members 35 having been omitted to more clearly show other important parts; Fig. 2 is a fragmentary plan view showing some of the tube-gripping members and tube guides; Fig. 3 is a side view of a gripping member with 40 a tube secured therein; Fig. 4 is a view similar to Fig. 3 but showing the gripping member in position for releasing or receiving a tube; Fig. 5 is a diagrammatic view of two tubes held by a pair of gripping members 45 and showing a bulge on one of the tubes produced by the upward movement of the lower gripping jaw; and Fig. 6 is a side view of a tube provided with a constriction formed by my machine.

50 Like numerals indicate similar parts throughout the several views.

The invention, as illustrated in the an-

nexed drawings, comprises a mechanism which includes an upper cylindrical member composed of discs 2 and 3 connected by 55 a hub 4. Below the upper member and contiguous thereto, is arranged a lower cylindrical member composed of discs 5 and 6 connected by hub 7.

The said cylindrical members are mounted 60 upon, and secured to, a vertical spindle 8. The lower end of the spindle is suitably reduced in diameter to provide a shoulder which bears on a support or table 10. The reduced portion of the spindle extends 65 through the table and a bearing 9, integral with the table and is provided with a worm wheel 12 which may be connected to any desirable source of power by means of a worm 11. When power is applied, the worm 70 drive causes the rotation of the spindle and the cylindrical-members attached thereto.

The upper cylindrical-member is provided with a plurality of passages or work-guides 75 15 spaced at intervals in annular formation, equally distant from the axial line of the spindle and adjacent to the peripheries of the discs. The said guides are composed of passages 16 and 17 in the upper and lower discs, respectively, and connecting tubes 18. 80 The upper cylindrical-member is of a greater diameter than the lower member to permit the arrangement of the guides in the required location for feeding the work to the proper position to be advanced. The enlarged diameter of the passage 15 allows for 85 the slight lateral movement of the lower end of a tube as it passes through the passage 16. Since the conveyor is continuously advanced during the feeding of the tubes thereto, a tube fed to the guides may have a tendency to tip out of the vertical but by reason of the enlarged guide, the tube will readily adjust itself during this downward movement.

90 The disc 5 of the lower cylindrical member is provided with a plurality of vertical recesses 21 that are uniformly spaced about its periphery, and the disc 6 is provided with a plurality of like recesses 22 similarly disposed. The said slots are located in the same radial planes as the guides 15 and are 95 equal in number to the said guides. 100

The recesses 22 are provided with heads

25 that are arranged to slide vertically therein. The recesses 21 are also provided with similar heads 24 which are, however, rigidly secured in place. The heads 24 and 5 25, are otherwise similar and are provided with projections 26 and 27 (see Fig. 2). A lever 28, having unequal arms, is pivoted between the projections 26 and 27 on a pin 23.

10 The short arm of the lever 28 projects toward the head and the oppositely projecting long arm is provided with a weight 30. In the present construction, the weight 30 is in the form of a roller, the function of which 15 will be hereinafter more fully explained.

The vertical face of each head is provided with groove 29 of angular shape. It will readily be understood that, when the weighted lever arm is free to drop, the short arm 20 will move toward the groove and press an object, such as a tube, against the groove 29 and secure it in place, the groove acting, in the case of a cylindrical object, to locate it centrally of the head. For the purpose of 25 preventing the head 25 from binding, I provide it with a counter weight 20.

Gripping-members of this character may be readily constructed to give the exact degree of pressure necessary to hold the object in position. This is especially advantageous in the present case where the objects to be handled are fragile. The gripping or clamping members are arranged in pairs, about the discs, and are adapted to 30 grip the ends of a tube applied thereto or to discharge a tube at the proper point.

For the purpose of reciprocating the sliding head 25, I provide it with a depending arm 39 having a roller 41 which rides on 40 the surface of a track 42. It will readily be seen that any variation in the surface 42 will cause a corresponding movement of the head and thus vary the distance between the upper and lower gripping members. Where 45 it is desirable to increase the distance between the upper and lower gripping members, a depression, as at 43 in Fig. 1, is provided and, as the roller 41 travels over the depression, the weight of the head 25 and its component parts causes it to drop 50 or move away from the upper gripping member. To make the downward movement of the members more positive, an overhanging ledge 44 is provided.

55 It is not necessary for the track 42 to completely surround the cylindrical members since stops 19 are provided to support the heads 25 when in their lowest positions. The lower gripping members will thus be 60 carried over any portion of their path of movement where it is found desirable to eliminate the track.

The levers 28 of the gripping members are operated by a means similar to that which

actuates the lower heads 25. For this purpose, continuous guides 45 and 46 are located below the weighted ends or rollers of the levers, the said guides having their surfaces undulated at the required places so that the rollers 30, when traversing the guides, will 70 act to lift the levers 28. The inclinations of the surfaces are so proportioned as to lift the levers as the rollers pass up an incline and to lower them as the rollers pass down an incline. 75

It will further be understood that the said undulations of the guides 45 and 46 are so disposed as to simultaneously actuate the upper and lower levers of each pair of gripping members. 80

The summit of the rise in each guide is located at the point where a tube is to be applied to, or removed from, the gripping members. It will readily be understood that, when the lever is rocked on its fulcrum, the 85 short arm acts either to grip an object as it is fed to the gripping members through the guides 15 or to permit it to drop into any suitable receptacle, which may be located beneath the table, a suitably located slot being 90 provided in the table for the passage of the tubes.

Intermediate the upper and lower gripping members are located two concentrically arranged gas burners 31 and 32. 95 The burner faces are substantially of flat form and have a multiplicity of holes 33 to provide jets of flame. The primary object of the burners is not to direct the flame into contact with the object to be softened but 100 to cooperate or coordinate one burner with the other to cause heat to emanate across the space 34 (see Fig. 2) between the burners and form what will hereinafter be termed a heat-passage or heat zone, and it is through 105 this passage that the portion of the object to be softened is drawn.

The gas burners extend over only a portion of the path traveled by the work-holding members and are supported by connection with gas inlet pipes 35 and 36 (the said pipes are indicated by dotted lines). 110

The foregoing description locates and identifies the various parts and their respective relations. I will now describe the 115 operation of the machine and the method of forming the constricted portion of a glass tube or rod.

In the following description, the cylindrical members which revolve with the spindle 8 will be referred to as a carriage, and this term, when used, particularly in the claims, is to be construed as identifying that part of the machine which receives, carries and delivers the work. 120

In the operation of the machine, the carriage is rotated, and the work, which, in the illustration, is in the form of glass tubes 50, 125

is successively delivered to the gripping members, at any suitable point, through passages 15. Coincident with this point and upon the surfaces 45 and 46, is a rise 51 (see Fig. 4) which lifts the levers 28 to permit each successive tube dropped in place to be secured by a pair of gripping members. When the tube is in place, a portion of its length is adapted to travel through the heated passage 34 existing between the two burners 31 and 32. To retain the tube in position before the gripping members have acted, a temporary support 60, is provided. The said support extends about the carriage a sufficient distance to carry the tube during the rotation of the carriage until the rollers 30 have traveled to their lowest position upon the surfaces 45 and 46, at which point the gripping members operate to secure the tube to be advanced. The support 60 is provided with a resilient surface, in the form of a flat spring 61, as illustrated in Fig. 4. This prevents breakage through impact with an otherwise inelastic surface when the tube is delivered or dropped from any suitable feeding device through the chute to the open gripping members.

The several tubes, having been secured by the gripping members, are advanced by the rotation of the carriage, whereby a portion of the several tubes passes through the heated zone.

As a given tube begins to reach the desired plastic state, attained while passing between the burners, the downward inclination of the track 42 permits the lower gripping member to drop and gradually elongate or stretch the plastic portion of the tube and, consequently to reduce its perimeter at that point. By this means, a gradual pulling or stretching of the softened section is accomplished and it is therefore possible to alter this portion of the tube without retarding the operation or stopping the work, as has heretofore been necessary.

The tube may be elongated either during the movement of the tube through the heated passage or immediately after the tube has left the said passage.

After the head 25 has dropped, and the constriction has been made in the tube, the rollers 30 travel over raised portions suitably located on the guides 45 and 46, thereby causing the levers to release the constricted tube.

In practicing my invention, it may be found desirable, when treating a tube having a relatively thin wall, to first compress or upset the portion to be constricted to increase the thickness of the wall at that point, preparatory to the elongation operation. A protuberance or bulge 52 is shown on the tube 50 (in Fig. 5) and indicates the thickened wall of the tube. This is accomplished by providing a raised portion 65 at a suit-

able point in the surface 42 over which the roller 41 passes. In this case, the raised portion acts to decrease the distance between the gripping members and compress the softened portion of the tube.

The exhaust tubes are necessarily a volume product, and my machine meets the demands of production with a small amount of attention on the part of an operator. In practice, the machine is equipped with any well known form of automatic feed and it is only necessary for an operator to keep the feed hopper filled with blanks. The machine receives the blanks, performs the necessary operation to each successive blank and deposits it in a receptacle.

Although I have shown a preferred embodiment of my invention, it is to be understood that many structural changes may be effected therein, and it is, therefore, to be understood that my invention is to be limited only by the scope of the appended claims. As an illustration of such structural changes, the elongation of the tube may be varied as desired according to the depth of the depression or undulation in the track. The width of the burners may also be varied according to the desired length of the portion of the tube to be made plastic.

What is claimed is:

1. A glass-working machine comprising means for producing a restricted heat zone, means for continuously moving a tubular body through said heat zone whereby heat is applied to a portion of the said tubular body, means for varying the length of the heated portion to alter the calibre of the said heated portion and means for discharging the altered tubular body from the machine.

2. A glass-working machine comprising means for providing an annular restricted heat zone, means for continuously moving a tubular body through said annular heated zone whereby heat is applied to a portion of the said tubular body, means for elongating the said heated portion and means for discharging said tubular body from the machine.

3. A glass-working machine comprising a plurality of work-holders arranged to support tubular bodies, two oppositely disposed concentric burners arranged to provide a restricted heated zone, mechanism operating to move the work holders and thereby cause sections of the tubular bodies to pass between the burners, means for stretching and thereby reducing the perimeter of the heated section and means for actuating said work-holders to release said tubular body.

4. A glass-working machine comprising a plurality of work-holders arranged to support tubular bodies, two oppositely disposed concentric burners arranged to provide a restricted heated zone, mechanism

- operating to move the work holders and thereby cause a section of the tubular bodies to pass between the burners, means for effecting the reduction of the perimeter of 5 the heated section and means for actuating said work-holders to permit the removal of said tubular bodies from the machine.
5. In a machine for reducing the cross sectional area of a tubular body, the combination with means for producing a restricted heated zone, means for gripping the ends of said body, means for moving said gripped body continuously through said zone to render plastic a portion of the 10 body intermediate its ends, mechanism adapted to elongate the body and cause a reduction in the calibre thereof at the plastic portion and means for causing a removal of said tubular body from the machine.
10. In a machine for reducing the diameter of a portion of the length of a tubular body, the combination with means for providing a circular restricted heat zone, 15 gripping members arranged to secure a tubular body at the ends thereof, means for moving said body to cause a portion thereof to travel through said heat zone until plastic, means for operating said gripping members for increasing the length of the plastic portion to reduce its diameter and means for actuating said gripping members to permit a discharge of said tubular body from the machine.
25. 7. A glass-working machine comprising a carriage, a plurality of work-gripping members arranged thereon, burners comprising oppositely positioned perforated surfaces adapted to provide a restricted heated passage, means for automatically operating the 30 gripping members to secure work inserted therein, means connected with the said carriage to rotate the same to move the work through the said heated passage, means for positively separating the gripping members to elongate the heated portion of the work, and means for opening the said members to release the work.
35. 8. In a machine for reducing the perimeter of a portion of the length of a relatively short section of a tube, the combination with a rotatable circular carriage, of a series of aligned upper and lower gripping members arranged about the periphery of 40 the carriage, guides through which tubes may be fed to the gripping members, a mechanism for actuating each of the said gripping members to secure a tube between pairs of said gripping members, burners comprising oppositely disposed perforated 45 walls arranged intermediate the gripping restricted members to produce a heat zone, means for rotating the carriage to continuously move the tubes through said zone, until a portion of each tube becomes plastic,
- means for moving the lower gripping member to effect a stretching of the several tubes, and a mechanism for releasing the said tubes from the gripping members.
9. A glass working machine comprising a 70 rotatable carriage having upper and lower discs, a plurality of work-gripping members secured at intervals around the periphery of the upper disc, a plurality of gripping members similarly disposed about the 75 periphery of the lower disc and adapted to move vertically in recesses, the said members being arranged to constitute a plurality of pairs each comprising one upper and one lower member, a work guide located above 80 each of the said pairs, mechanism for actuating a pair of the gripping members to secure work fed thereto through the guides, burners arranged to heat a portion of the work, means for rotating the carriage, means 85 for moving the lower gripping member downwardly to elongate the work and alter the heated portion, and means for actuating each successive pair of gripping members to release the work.
10. A machine for reducing the perimeter of a portion of the length of a tube comprising a rotatable carriage, tube-gripping members consisting of an upper head arranged 90 to be secured in a fixed relation to the carriage, a lower head arranged to be reciprocated vertically in recesses in the carriage, the said heads being provided with outwardly extended bearings, a groove formed 95 in the head and between the bearings, levers mounted in the bearings, means for operating the levers to secure a tube between one arm of each of the levers and the said groove, means for applying heat to the tube and means for moving the said lower head 100 to elongate the said tube.
11. A machine for reducing the perimeter of a portion of the length of a tube comprising a rotatable carriage, said carriage including tube-gripping members consisting 105 of an upper head arranged to be secured in a fixed relation to the carriage, a lower head arranged to slide vertically in recesses in the carriage, the said heads being provided with outwardly extended bearings and groove 110 formed in the head and between the bearings, double-arm levers mounted in the bearings, one arm of each of the said levers being weighted whereby the opposite arm is normally held in such relation to the said groove as to secure a tube thereto, means for applying heat to a tube thus secured, means for moving the said lower head to elongate 115 the tube to alter its heated portion, and means for operating the levers simultaneously to release the tube.
12. A machine for reducing the perimeter of a portion of the length of a tube comprising a rotatable carriage, said carriage including tube-gripping members consisting 120 of an upper head arranged to be secured in a fixed relation to the carriage, a lower head arranged to slide vertically in recesses in the carriage, the said heads being provided with outwardly extended bearings and groove 125 formed in the head and between the bearings, double-arm levers mounted in the bearings, one arm of each of the said levers being weighted whereby the opposite arm is normally held in such relation to the said groove as to secure a tube thereto, means for applying heat to a tube thus secured, means for moving the said lower head to elongate the tube to alter its heated portion, and means for operating the levers simultaneously to release the tube.

of an upper head arranged to be secured in a fixed relation to the carriage, a lower head arranged to slide vertically in slots upon the carriage, the said heads being provided 5 with outwardly extended bearings, an angular groove formed in the head and between the bearings, double-arm levers mounted in the bearings, one arm of each of the said levers being weighted whereby the opposite 10 arm is normally held in such relation to the groove as to secure a tube in contact therewith, means for applying heat to a portion of the tube when secured by the gripping members, means for moving the lower 15 head to elongate the said tube and alter its perimeter, guide surfaces arranged below the weighted arms of the levers, undulations upon the said surfaces, means for rotating the carriage whereby the weighted arms are 20 caused to travel up the undulated surfaces and thereby move the opposite arms to release the elongated tubes.

13. A machine for reducing the perimeter of a portion of the length of a tube comprising 25 a rotatable carriage, means for rotating the same, said carriage including tube-gripping members consisting of an upper head arranged to be secured in a fixed relation to the carriage, a lower head arranged 30 to slide vertically in slots upon the carriage, the said heads being provided with outwardly extended bearings, an angular groove formed in the head and between the bearings, levers mounted in the bearings, the said 35 lower head being provided with depending bearings and rollers, a track to afford a bearing for the said rollers, means for operating the levers to secure tubes between the end of the levers and grooves, burners for applying 40 heat to a portion of each of the said tubes, a depressed portion in the said track whereby the lower heads are permitted to drop and thereby elongate the heated tubes as the carriage is rotated, and means for 45 actuating the levers to release the altered tube.

14. A machine for reducing the perimeter of a portion of the length of a tube comprising 50 a rotatable carriage, means for rotating the carriage, said carriage including tube-gripping members consisting of an upper head arranged to be secured in a fixed relation to the carriage, a lower head arranged 55 to slide vertically in recesses in the carriage, the said heads being provided with outwardly extended bearings, an angular groove formed in the head and between the bearings, double-arm levers mounted in the bearings, the said lower head being provided 60 with a depending bearing and a roller, a track to afford a bearing for the said roller; means for operating the levers to secure tubes between the ends of the levers and the 65 grooves, two concentrically arranged burners forming a heated path for the passage

of a portion of each of the tubes during their rotation with the carriage, a depression in the said track whereby the lower gripping members are caused to move away from the upper gripping members to effect the elongation 70 of the heated tube during the rotation of the carriage, and means for actuating the double levers to discharge the tube.

15. A machine for reducing the perimeter of a portion of the length of a tube comprising 75 a rotatable carriage, means for rotating the carriage, said carriage including tube-gripping members consisting of an upper head arranged to be secured in a fixed relation to the carriage, a lower head arranged 80 to slide vertically in recesses in the carriage, the said heads being provided with outwardly extended bearings, an angular groove formed in the head and between the bearings, double levers mounted in the bearings, 85 the said lower head being provided with a depending bearing having a roller thereon, a track to afford a bearing for the said roller, means for operating the levers to secure a tube between the ends of the levers and the 90 groove, burners arranged to provide a heated course for the passage of a tube whereby a portion of the tube may be made plastic, a depression and an elevation upon the said track to cause, first a compression of the 95 heated portion and second an elongation of the heated portion as the lower head rises and falls during the rotation of the carriage, and means for actuating the above mentioned levers to release the said tube. 100

16. A device for holding glass tubes, or the like, comprising a head having a groove, bearing arms projecting from the said head at the sides of said groove, a lever pivoted between the bearing arms, and a weight at 105 one end of said lever adapted by means of its potential energy to effect an engagement between the opposite end of said lever and a body disposed in said groove.

17. A device for holding glass tubes, or the like, comprising a head having an angular groove, bearing arms projecting from the head at the sides of said groove a lever pivoted between said bearing arms and having a weight upon its outer end whereby the 115 opposite end is caused to move toward the head and secure an object within the said groove.

18. A work holder comprising a head and a support therefor, bearing arms projecting outwardly from the head, a lever comprising a long and a short arm and having a weight upon its long arm mounted between the said bearing arms and a groove located in the head between the bearing arms, the short 120 arm of said lever being movable toward said groove by reason of the weight upon said long arm.

19. A device for holding glass tubes, or the like, comprising a carriage, heads ar- 130

ranged to be reciprocated vertically upon the said carriage, bearing arms projecting from the heads, a double-arm lever mounted between the said bearing arms, a groove upon 5 each of the heads and located between the bearing arms, and a weight upon one of the lever arms whereby the other arm is ac-

tuated toward the groove to press a tube in contact therewith.

In testimony whereof, I have hereunto ¹⁰ subscribed my name this 8th day of December, 1920.

HARRY D. MADDEN.
